UNITED STATES PATENT OFFICE.

ALBERT P. GOLDMAN AND HOWARD H. STEPHENS, OF NORTH CHILlicoTHE, ILLINOIS,
ASSIGNORS OF ONE-THIRD TO JOHN W. TOBIN, OF NORTH CHILlicoTHE, ILLINOIS.

CAR-COUPING.

No. 897,889.

Specification of Letters Patent.

Patented Sept. 8, 1908.

Application filed April 3, 1906. Serial No. 309,626.

To all whom it may concern:

Be it known that we, ALBERT P. GOLDMAN and HOWARD H. STEPHENS, citizens of the United States, residing at North Chillicothe, 5 in the county of Peoria and State of Illinois, have invented a new and useful Improvement in Car-Couplers, of which the following is a specification.

This invention relates to a car coupler, and 10 the object of the invention is a coupling which cannot when broken or disengaged, drop down or interfere in any way with the running gear of the cars.

Another object of the invention is a coupler 15 in which co-acting parts will be prevented from slipping past each other, while coupled by reason of the unevenness in the height of the cars, or irregularity in the road bed.

Still further objects of the invention are to 20 provide a coupler in which all strain is removed from the pivot pin in which the knuckle will automatically lock and finally an object of the invention is to provide a new 25 form of lock for the purpose of locking the knuckle in closed position.

In these drawings forming a part of the specification:—Figure 1 is a perspective view showing the knuckle in open position. Fig. 2 is a detail perspective view showing the 30 knuckle closed and locked. Fig. 3 is a detail perspective view of the knuckle. Fig. 4 is a detail perspective view of a lock adapted to coöperate with the knuckle. Fig. 5 is a detail perspective view of a combined operating 35 pin and latch. Fig. 6 is a horizontal section taken lengthwise through the coupler head and a portion of the draw bar and showing the knuckle and locking means in plan. Fig. 7 is a section on the line 7—7 of Fig. 6, showing 40 the position of parts locked. Fig. 8 is a section on the same line looking in the opposite direction. Fig. 9 is a section on the line 9—9 of Fig. 6.

In these drawings A represents a draw bar 45 provided with a coupler head A', the front face of which is provided with a concavity A² and this front concaved face is recessed as shown at A³, in Fig. 2 the said recess being adapted to receive a suitable knuckle. A 50 vertical slot A⁵ opens upwardly through the top of the coupler head A' and at its lower end communicates with the recess A³. The coupler head is provided upon one side of the concavity A², with upper and lower lugs A⁴ 55 and a knuckle B is provided with a perfo-

rated cylindrical bearing portion B' which is journaled between the lugs A⁴ and is held in place by a suitable pin D which passes through the lugs A⁴ and through the perforations of the bearing portion B' of the knuckle 60 B. The bearing portion B' is provided with a finger B² which is formed upon its inner face with an inwardly projecting portion B³, midway its ends, and at its end the finger B², carries a projecting shoulder B⁴ which extends outwardly. 65

A co-acting locking member C rests loosely within the recess A³ of the coupler head A', and the locking member C is provided with a 70 forwardly projecting angled hook portion C', slightly recessed upon its upper edge as shown at C². The said locking member is also provided with a squared shoulder C³ which projects forwardly parallel to the main body of the hook portion C' and parallel to and adjacent the recessed portion C². An operating lever and latch E is cut away 75 adjacent its upper end to form a shoulder E', and the end portions of said latch are perforated as shown at E², to form an eye. We 80 also slot the rear face of the locking member C as shown in Fig. 6, at C⁴, and the operating lever E is pivoted to the locking member C in the slot C⁴. To prevent the knuckle B from swinging entirely out of the coupler 85 head, it is provided with a raised shoulder B⁵, which acts as a stop, when the coupler is thrown into open position by engaging the upper inner edge of the front wall of the recess A³. 90

A cross strip D' is secured within the coupler head A' extending from the front to the rear and rearwardly and upwardly, and this strip is engaged by the recessed portion 95 C² of the locking member C when the same is lifted by the latch or lever E, thereby permitting the locking member C to rock on the under face of the cross piece D'.

When in position the locking member C 100 rests upon the bottom of the recess A³, which is slightly lower by three-fourths of an inch, than the under face of the locking finger B² of the knuckle B. The lever E extends upwardly through the slot A³, and its normal position in the slot is indicated in Fig. 2, only the top of the upper end projecting from the upper end of the slot. The perforation in the upper end of the lever E can be used for the purpose of securing a chain, link, or rod 105 to the said upper end. When it is desired to 110

uncouple the cars the lever E is moved toward the center of the slot A³, until the shoulder E' which has been in engagement with the upper wall of the recesses A³ clears the 5 said wall, and the lever E can then be lifted into the position shown in Figs. 1 and 8, bringing the shoulder E' through and out of the slot A³. This movement of the lever E will lift the locking member C vertically and 10 a distance sufficient to clear the finger B², of the knuckle B and the recess C² formed upon the hook member C' will strike the cross piece D' upon which it will rock, as the lever E is lifted and this rocking or turning move- 15 ment of the lock C will cause its hook member C' to engage the knuckle upon the rear side of the shoulder B⁵ and upon the finger B², thus throwing the finger B² outwardly into position shown in Fig. 1. With the knuckle in 20 open position and the lock in its elevated position the lock rests loosely upon the upper edge of the shoulder B⁵ which not only serves as a stop to prevent the knuckle being entirely disengaged from the recess A³ but 25 also prevents the lock C dropping in to said recess in rear of the knuckle. When the knuckle is in this, its open position, the co-acting knuckle carried by the other car, is also set in open position and the two cars 30 permitted to come together with the knuckles in open position. The engagement of the two knuckles will automatically swing the knuckle B into the position shown in Fig. 2 carrying the locking finger B² back into the 35 recess A³ and forcing the locking member C back into its normal or perpendicular position, and it thereupon drops by gravity to the bottom of the recess and the shoulder E', falling below the lower end of the slot A³ 40 again becomes locked against the upper wall of the recess A³ and cannot be opened until

the locking member C is again lifted, as the shoulder B⁴ is in engagement with the lock C, and the knuckle finger B² fits in the space formed between the body of the lock C and 45 the angled hook member C'.

Having thus fully described our invention, what we claim as new and desire to secure by Letters Patent, is:—

1. A coupler comprising a recessed head, a 50 knuckle having a finger projecting into said head, a shoulder on said finger engaging the inner upper edge of the recess when the knuckle is in open position, an angled, vertically movable locking member adapted to 55 lock the knuckle against outward movement when the locking member is in its lowest normal position and means for lifting the locking member and forcing the knuckle into open position, the locking member resting 60 on the shoulder above mentioned when in its highest position.

2. A car coupler comprising a coupler head having a recess formed in its front face and a vertical slot communicating in its lower end 65 with said recess, a pivoted knuckle having a finger adapted to work in the said recess, the said finger having a shoulder formed thereon, an angled locking member resting loosely within the recess and adapted to receive and 70 lock the knuckle finger in a closed position, and a lever connected at its lower end with the locking member, said lever resting in the vertical slot and movable in said slot for the purpose of lifting the locking member clear 75 of the knuckle finger.

ALBERT P. GOLDMAN.
